his ATTORNEY

UNITED STATES PATENT OFFICE.

AMOS H. SMITH, OF BROOKLYN, NEW YORK, ASSIGNOR TO AMERICAN BANK NOTE COMPANY, OF NEW YORK, N. Y., A CORPORATION OF NEW YORK.

ROTARY PLATE-PRINTING MACHINE.

Application filed August 6, 1918. Serial No. 248,518.

To all whom it may concern:

Be it known that I, AMOS H. SMITH, a citizen of the United States, residing at the borough of Brooklyn, in the city of New York, county of Kings, and State of New York, have invented certain new and useful Improvements in Rotary Plate-Printing Machines, of which the following is a specification, reference being had thereto in to the accompanying drawings, which form a part thereof.

My invention relates to rotary plate printing machines, and more particularly to a machine of this character adapted to be used in making impressions from a single plate, as distinguished from rotary machines employing a plurality of plates upon the form or plate cylinder.

In plate printing machines in which the imprint is made from an intaglio, engraved, or under surface printing plate, the printing conditions differ from those in machines used in printing from cameo or relief plates, not only in the nature of the plate used, but in the character of the ink, the degree of pressure from the impression cylinder to secure the imprint, and the time required to secure the proper transfer of the ink contained in the lines of the plate to the paper.

Heretofore, it has been possible to utilize rotary plate machines economically only when making a very large number of impressions, since the duplication of plates, and the make-ready of the press is too expensive to justify the production or use of more than a single plate for a short run, and the use of a single plate on a multiple plate machine entails a material curtailment in the capacity of the machine. Hence it has been the practice, when only one plate is produced for a job, to use a flat bed press, the capacity of which is very limited compared with other types of presses using a plurality of plates.

With these conditions in mind, the object of my invention has been to produce a rotary printing press, the form or plate cylinder of which is adapted to have a single plate mounted thereon, other mechanisms associated with said plate cylinder being so combined and associated therewith as to permit the development of a capacity in the machine much greater than can be obtained with a single plate, flat bed machine,

and approximately equal to that of a multiple plate machine. To secure this result, it is essential to increase the R. P. M. of the form or plate cylinder, while affording ample time for the proper wiping and polishing of the plate and the making of a proper imprint therefrom. By means of a printing machine made in accordance with my invention, I am enabled to secure the desired capacity from a single plate, while preserving all those time elements essential to the proper preparation of the plate, and the proper making of an imprint.

In addition to providing a printing machine having the above characteristics, I have so associated the various elements as to permit the feeding of the paper to, and their collection from, the printing couple, under conditions ensuring an effective transfer of the ink from the plate to said sheets.

The invention consists primarily in a rotary plate printing machine embodying therein a form or plate cylinder adapted to receive a single plate, an inking mechanism, a wiping mechanism, a polishing mechanism, an impression cylinder or D-roll associated with said form or plate cylinder, and means rotating said form or plate cylinder at a high speed, determined by the minimum time required by said wiping mechanism to wipe the plate and pack the lines thereof with the ink, and in such other novel features of construction and combination of parts as are hereinafter set forth and described, and more particularly pointed out in the claims hereto appended.

In the accompanying drawing I have shown a vertical section of a printing machine embodying the essential characteristics of my invention, the actuating means for the inking mechanism, and for the wiping and polishing mechanisms being omitted, as such are immaterial to my present invention.

In the embodiment of my invention shown in the drawings, I employ a plate or form cylinder *a* adapted to receive a single engraved, intaglio or under-surface printing plate *b*, the length of this plate being approximately 180° of the periphery of said cylinder. This cylinder *a* is of short radius compared with the form or plate cylinders of rotary machines heretofore used, the diameter of the cylinder being made as small as possible with due regard to the

maximum size of the plate to be used thereon, and the ability to impart to said plate, which is hardened steel, the desired curvature. The use of a cylinder of small diameter permits an increase in the number of revolutions of the cylinder per minute without varying the peripheral speed of the cylinder, or the rate of traverse of the plate, as compared with a plate upon a cylinder of 5 larger diameter, such as is used in a multiple plate machine. Hence, for example, if the cylinder be made one-half the diameter of the cylinder of a multiple plate machine, the speed of this cylinder may be doubled, 10 and yet maintain all of the conditions surrounding the inking, wiping and polishing of the plate, and the making of the imprint. Since it is impossible to bend a plate in an arc of more than 180°, or mount it upon a 15 cylinder, if the plate is of an arc greater than that specified, my invention is limited to the use of a form cylinder *a* having a plate of no more than approximately 180° in length thereon. The opposite diameter 20 of said cylinder is counterweighted as shown at *a'*, to compensate for the load of the plate, and of the surface supporting 25 same.

Associated with the cylinder *a* is an inking mechanism consisting of the usual ink fountain *c*, distributing rollers *d*, and inking rollers *e*, wiping platens *f* and *g* having the usual wiping cloth *h*, and a polishing platen *i* having the usual polishing cloth *j* passing 30 over same. These mechanisms are each old and well known in this art, no claim of invention being made thereto, except broadly as elements in the combination of a machine made in accordance with my invention. 35

Also associated with the cylinder *a* is an impression cylinder or D-roll *k*, carrying gripper fingers *m* adapted to engage a sheet of paper delivered from the feed shelf 40. Any desired form of gripper mechanism may be used. The impression cylinder, or D-roll *k*, is of relatively smaller diameter than the cylinder *a*.

I have not shown the actuating means for 45 the impression cylinder or D-roll *k*, it being understood that this cylinder is intermittently operative in the usual and well known manner, to ensure the proper timing of its operation with relation to the form or plate cylinder *a*. Said impression cylinder or D-roll *k* is mounted at one side, or upon a horizontal radius of the cylinder *a* and is so mounted as to develop the necessary pressure to secure a proper imprint, and cause 55 the frictional engagement thereof with the sheet contained between the cylinder *a* and the plate *b*, to feed said sheet in relation to said plate, while allowing it to remain on the plate, after the impression has been 60 made, for a sufficient interval, to ensure the 65

proper transfer of ink from the lines of said plate to the paper before said paper is removed by the collecting mechanism. In order to afford this dwell of the paper upon the plate, I arrange the collecting mechanism *o* which may be of any desired type, at the top of the cylinder *a*, or approximately 70 90° beyond the printing point.

The operation of the herein described machine is substantially as follows:— 75

When operating a press made in accordance with my invention, the cylinder *a* is rotated at a speed which will develop a peripheral speed, or rate of travel of the plate *b* as high as is possible, or consistent, 80 with a proper preparation of the plate for the making of the imprint. This peripheral speed or travel approximates, or is substantially the same as, that of the plates upon a multiple plate machine of the rotary type, and is greater than that of such a machine of the flat bed type. Assuming that the cylinder *a* is one-half the diameter of the cylinder of a two plate rotary machine, by having the speed of rotation of 85 said cylinder *a* double that of the cylinder of the two plate machine, it will be seen that the plate *b* will be brought into the printing relation with the impression cylinder or D-roll *k* twice, while each of the 90 plates upon the larger cylinder will be brought into this relation but once, and hence that the capacity of the two machines will be equal. If, however, the ratio of the diameters of the cylinder *a* and of the 95 cylinder upon the two plate machine, be greater than one to two, it will be necessary to reduce the speed of rotation of the cylinder *a* proportionately, and there will be a corresponding variance in the capacity 100 of the two types of presses, and while the output of the single plate machine will be relatively smaller than that of the two plate machine, the time afforded for the conditioning of the plate and the making of the 105 imprint upon the single plate machine will be the same. To preserve the desired conditions in a machine made in accordance 110 with my invention, as compared with those in a multiple plate machine, it is apparent 115 that the comparative speed of the cylinders in the two types of machines must be substantially in inverse ratio to the difference in the diameters of the plate or form cylinders of said machines. Since the capacity 120 of a multiple plate cylinder machine is very much greater than that of any flat bed plate machine, even of the multiple plate type, it is apparent that the capacity of a machine made in accordance with my invention, being approximately that of a multiple plate rotary machine, will of necessity be greater than that of any type of flat bed machine, and particularly of a single plate 125 machine of the flat plate type. 130

Since but one plate is required for use upon the cylinder *a*, it is apparent that the desired high capacity can be secured under substantially the same printing conditions, 5 as in a rotary plate machine of the two plate type, excepting as to the wear upon the plate, thus making a machine made in accordance with my invention, particularly adaptable for use upon short runs, the 10 length of which would not justify the duplication of plates. Furthermore, the make-ready of a machine made in accordance with my invention requires less labor, may be more quickly accomplished, and is therefore 15 less expensive than the make-ready of a multiple plate machine.

With each rotation of the cylinder *a*, the plate *b* thereon is brought successively into the operative relation to the inking 20 rollers *e*, the wiping cloth *h* and the polishing cloth *j* for properly conditioning, or preparing, the plate, the impression cylinder *k*, and the collecting mechanism *o*.

The inking operation and the polishing 25 operation do not place any limitation upon the peripheral speed at which the plate *b* may be driven, but the proper wiping of the plate and packing of the lines with the ink, I have discovered cannot be 30 accomplished if this speed is too high. It is also desirable, to secure a proper imprint, that the speed of the plate, during the impression interval, shall not be too high. As a consequence, the functions of the wiping 35 mechanism and the impression cylinder place certain limitations as to the speed of rotation of the plate cylinder. The making of the imprint may be secured at a relatively higher speed, however, than the wiping 40 of the plate, particularly if the sheet be allowed to remain upon the plate for a substantial period after the impression cylinder or D-roll is operative in making the imprint, since this dwell of the sheet upon 45 the plate tends to ensure a better bond of the ink to the paper, and, therefore, a more complete transfer of the ink from the lines of the plate to the paper. By reason of the fact that damped sheets of paper are employed, there is a tendency of the paper to 50 remain in the lines of the plate after they have been once pressed thereinto by the impression cylinder or D-roll.

The wiping platens *f* and *g* and the polishing platens *i* receive movement axially of the cylinder *a*, or substantially so, in the same manner as is usually employed in plate printing presses.

The impression cylinder or D-roll *k* need 60 be only of a diameter sufficient to cause the blanketed surface thereon to be of a length approximately that of the plate upon the cylinder *a*, and hence the cylinder or D-roll will receive one full rotation during 65 only a partial rotation of said cylinder *a*,

said impression cylinder or D-roll remaining stationary during that portion of each rotation of the cylinder *a* when the plate *b* is being inked, wiped and polished. Hence the impression cylinder or D-roll is intermittently rotated. The actuating means for securing this result is old and well known in this art, however, and is not illustrated in the accompanying drawings.

The collecting mechanism *o* removes the 70 sheets from the plate *b* just prior to the inking of said plate upon the subsequent cycle of operation.

I believe it to be broadly new to provide a rotary plate printing machine wherein 80 the form cylinder is adapted to receive a single plate, and is rotated at a high speed determined by the time required by the wiping mechanism to properly wipe the non-printing surface of the plate, and pack the ink in the lines thereof. I also believe it to be novel to provide a machine of this character wherein the sheets of paper are delivered to the impression cylinder, and after delivery thereby in the printing position in relation to the form or plate cylinder, are allowed to remain upon the plate for a substantial interval of time, to afford such a dwell as will ensure a more effective 85 transfer of the ink contained in the lines of the plate to the paper, before being removed from the plate by the collecting mechanism.

It is not my intention to limit the invention to the precise details of construction, shown in the accompanying drawings, 90 it being apparent that such may be varied without departing from the spirit and scope of the invention.

Having described the invention what I 105 claim as new, and desire to have protected by Letters Patent, is:—

1. A rotary plate printing machine embodying therein a form or plate cylinder adapted to receive a single plate, an inking mechanism, a wiping mechanism, a polishing mechanism, an impression cylinder or D-roll associated with said form or plate cylinder, means rotating said form or plate cylinder at a high speed, determined by the 110 minimum time required by said wiping mechanism to wipe the plate and pack the lines thereof with the ink, a gripper mechanism carried by said impression cylinder or D-roll, and a collecting or delivery mechanism adapted to remove sheets from the plate upon said form or plate cylinder, said collecting or delivery mechanism being spaced away from said impression cylinder or D-roll for a sufficient distance to permit 115 a dwell of the paper upon said plate after the impression has been made.

2. A rotary plate printing machine embodying therein a form or plate cylinder adapted to receive an engraved, intaglio or 120

- under-surface printing plate having an arc of approximately 180° of the circumference of said cylinder, an inking mechanism, a wiping mechanism, a polishing mechanism, 5 an impression cylinder or D-roll associated with said form or plate cylinder, means rotating said form or plate cylinder at a high speed, determined by the minimum time required by said wiping mechanism to wipe 10 the plate and pack the lines thereof with the ink, a gripper mechanism carried by said impression cylinder or D-roll, and a collecting or delivery mechanism adapted to remove sheets from the plate upon said form 15 or plate cylinder, said collecting or delivery mechanism being spaced away from said impression cylinder or D-roll for a sufficient distance to permit a dwell of the paper upon said plate after the impression has been 20 made.
3. A rotary plate printing machine embodying therein a form or plate cylinder adapted to receive a single plate, an inking mechanism, a wiping mechanism, a polishing mechanism, an impression cylinder or 25 D-roll associated with said form or plate cylinder, means rotating said form or plate cylinder at a high speed, determined by the minimum time required by said wiping mechanism to wipe 30 the plate and pack the lines thereof with the ink, a gripper mechanism carried by said impression cylinder or D-roll, and a collecting or delivery mechanism adapted to remove sheets from the plate upon said form or plate cylinder, said 35
- collecting or delivery mechanism being spaced away from said impression cylinder or D-roll, approximately 90°, whereby a dwell of the paper upon said plate, after the impression has been made, is permitted. 40
4. A rotary plate printing machine embodying therein a form or plate cylinder adapted to receive an engraved, intaglio or under-surface printing plate having an arc of approximately 180° of the circumference 45 of said cylinder, an inking mechanism, a wiping mechanism, a polishing mechanism, an impression cylinder or D-roll associated with said form or plate cylinder, means rotating said form or plate cylinder at a high 50 speed, determined by the minimum time required by said wiping mechanism to wipe the plate and pack the lines thereof with the ink, a gripper mechanism carried by said impression cylinder or D-roll, and a collecting or delivery mechanism adapted to remove sheets from the plate upon said form or plate cylinder, said collecting or delivery mechanism being spaced away from said impression cylinder or D-roll, approximately 55 90°, whereby a dwell of the paper upon said plate, after the impression has been made, is permitted. 60
- In witness whereof I have hereunto affixed my signature this 18th day of July, 1918, in the presence of two subscribing witnesses.
- AMOS H. SMITH.
